UNITED STATES PATENT OFFICE.

SAMUEL OTIS HALE, OF WHITTIER, CALIFORNIA.

WELL DERRICK.

Application filed January 9, 1925. Serial No. 1,445.

This invention relates to improvements in the construction of well derricks of the general type disclosed in my co-pending application for patent bearing Serial Number 698,471, filed in the U. S. Patent Office March 11, 1924. In the above mentioned application the vertical corner timbers are formed in sections, corner clamps being provided for rigidly securing adjacent timber ends together, a plurality of adjustable rods and girths being employed to stabilize the derrick structure.

The improvements illustrated and described in this application relate mainly to an improved method of bracing the vertical timbers, and at the same time to provide a more efficient socketed clamping means for the sectional timbers, the said means being adjustable to provide for inequalities in the sizes of the end of the timbers that are engaged thereby, such inequalities in size being mainly due to shrinkage.

By means of my improved construction greater economy in manufacture is effected, a substantial saving in time of erection is also accomplished.

The above and other objects are accomplished by means of the construction disclosed in the accompanying specification, reference being had to the drawing forming a part thereof, in which:

Fig. 1 is a side elevation of a complete well derrick constructed according to my invention.

Fig. 2 is an enlarged sectional plan view of the same taken on line 2—2 of Fig. 1.

Fig. 3 is an enlarged partial side elevation of the derrick.

Fig. 4 is an enlarged side elevation of one of the derrick corner clamps, portions being broken away to disclose interior constructions, the truss girt beams and adjusting rods being shown attached to the clamp.

Fig. 5 is a plan view of the above.

Fig. 6 is a perspective view of a corner clamp showing its interior construction.

Referring more specifically to the drawings the derrick structure, as in my heretofore described application, consists of four vertically disposed corner timbers, each formed of a plurality of sections 10, 11, 12, the ends being coupled together by means of corner clamps 13 formed of heavy gauge plate iron and bent in a right angle formation as shown in Fig. 6, the clamps engaging the outer faces of the abutting ends of the

vertical timbers. The leg members 14, 15, of each angle clamp are provided with a series of bolt holes 16 arranged in vertical formation for the reception of the ends of a plurality of rods 17 bent into right angles adapted to form with the corner clamps rectangular timber receiving sockets, the ends of the rods being threaded for the reception of nuts 18, by means of which the same may be adjusted to securely clamp the ends of the coupled timbers when inserted therein. As the timber receiving socket of each clamp is formed of a plurality of adjustable angular rods as above described, I am enabled not only to securely and rigidly clamp the abutting ends of the derrick timbers together, but such adjustment avoids the necessity of cutting away any portion of the timbers, which oftentimes is necessary in the case of fixed sockets due mainly to varying sizes of the timbers. Also it will be evident that should the clamped ends of the timbers shrink due to the "greenness" of the timbers, the angular rods may be quickly and easily adjusted.

Each corner clamp is provided with a flat key 20 secured by welding to the corner of the clamps, and extending towards the corners of the angle bars, terminating approximately midway the distance between the corners of the clamps and bars. The keys are located midway the height of the clamps and are designed to engage diagonally disposed key slots 21 formed in the ends of the abutting timber sections, as clearly shown in Figs. 4 and 5 of the drawings, when said sections are in place in the socketed clamps. These keys not only materially assist in rigidly maintaining the sectional timbers in a vertical position but prevent any turning or twisting movement imparted thereto by reason of the operation of the heavy drilling mechanisms connected to the derrick structure.

In order to effectually stabilize the derrick structure the oppositely disposed ends of adjacent corner clamps 13, are tied together by means of horizontally disposed girths 25, preferably formed of angle irons 26, 27, bent intermediate their ends into truss form, and secured together at their contacting portions 28 by means of bolts 29, their ends being bolted or otherwise secured to the ends of the corner clamp members.

By employing angle iron girths of truss formation their bracing action is greatly in-

creased, all lateral or vertical strains or twisting actions of the timbers being absorbed thereby, the angularity of the irons 26, 27, also contributing in no small degree to the rigidity of the derrick structure.

Turnbuckle tension rods 30 are also employed, as in my previous application, for truing and bracing the derrick structure, the rods being arranged diagonally, their hooked 10 ends engaging apertures 31 formed in the ends of the corner clamp members as clearly shown in the various views of the drawings. By means of these tension rods should the derrick get out of plumb due to a settling of the ground on which it is erected, or by warping of the vertical sectional timbers, the structure may be readily returned 15 to a normal position by an adjustment of the turnbuckles.

20 In order to provide an entrance for operators into the derrick, the lowermost ends of one side is provided with a door opening 32, formed by securing the ends of a pair of vertically disposed flat bars 33, spaced 25 apart to a cross bar 34 and the lowermost truss girth 35 as shown in Fig. 1.

Secured to the vertical door bars 33, and to the corner clamps directly above the derrick floor 36 are short girth bars 37, formed 30 in exactly the same manner as the other

girths 25, heretofore described, short turnbuckle tension rods 38, diagonally disposed connecting the three lowermost pairs of corner clamps with the vertical bars 33 that form the derrick entrance opening.

35 From the above description it will be apparent that I have provided a sectional derrick structure that may be easily assembled in position, the adjustable corner clamps and turnbuckle tension rods providing means whereby the structure may at all times be maintained in an adjusted position.

What I claim is:

A metal timber receiving socket for well derrick timbers comprising an angular plate 45 for engaging the outer sides of two abutting timbers, the two halves of said plate being of a width to extend beyond the timbers, a timber key secured in the corner of the angular plate adapted to engage key ways formed 50 in the abutting ends of timbers, whereby to maintain the timbers against a turning or twisting movement during an operation of the drilling mechanism, and a plurality of angular timber clamping bolts adjustably secured to the halves of the angular plate.

55 In witness that I claim the foregoing I have hereunto subscribed my name this 5th day of November, 1924.

SAMUEL OTIS HALE.
